UNITED STATES PATENT OFFICE.

PATRICK McCARTHY, OF BROOKLYN, NEW YORK.

VEHICLE-THEIF-INDICATING SIGN.

1,315,374.

Specification of Letters Patent. Patented Sept. 9, 1919.

Application filed April 17, 1917. Serial No. 162,619.

To all whom it may concern:

Be it known that I, PATRICK McCARTHY, a citizen of the United States, residing in Brooklyn, in the county of Kings and State 5 of New York, have invented certain new and useful Improvements in Vehicle-Thief-Indicating Signs, of which the following is a specification.

The object of my invention is to provide 10 an automatic signaling mechanism for use on automobiles, motorboats and such craft, which upon the attempted operation of the same by an unauthorized person will by a suitable visual signal indicate that a theft 15 thereof is being attempted.

To such ends my said invention comprises in substance a signal-plate having thereon the word "Stolen," or "Stop thief" or some such word or words, indicating the unauthorized use of the machine, which is normally covered and concealed from view; but on the unauthorized movement of the vehicle, will be instantaneously displayed to view from both front and rear; which signal plate is easily and quickly rendered incapable of being brought to view by the owner or authorized chauffeur by the use of a suitable key, which key when reversely operated will so adjust the plate as to be 20 immediately thrown into position by the starting of the motor or car; and while as shown and described herein the same is actuated by an electric-current, derived from the generator through the ignition circuit, 25 which ignition circuit cannot be closed except by an authorized person, in some cases and where the motors or vehicles are not provided with electricity, other suitable mechanism for displaying such a visual-signal other than the electric one described 30 above, actuated by any suitable power, may be used with the same effect.

My said invention is fully shown, described, and claimed in the following specification, of which the accompanying drawings form a part, wherein similar letters or numerals of reference designate like or equivalent parts wherever found throughout the same and in which:—

Figure 1 is a front face view of the signaling mechanism of my improved form, attached to a wind-shield, the rear of the casing being partially broken away to more

clearly show the mechanism, the concealed position of the signal plate being shown in 55 full lines, and extended signaling position being shown in dotted lines, except the wording which is in full lines.

Fig. 2 is a view in detail of the switch mechanism, lock and rack forming a portion 60 of the mechanism shown in Fig. 1, showing the same in the non-actuating position when being operated by those authorized.

Fig. 3 is a top plan view taken in section 65 on the line 3—3 of Fig. 1, looking downward in the direction of the arrows of the signal sign-box or housing, and the wind-shield being shown in section.

Fig. 4 is a view of such visual signal 70 mechanism, etc., taken in horizontal section (looking upward in the direction of the arrows) 4—4 of Fig. 1.

Fig. 5 is a diagrammatic view of the electric wiring and other mechanisms, connected 75 therewith; and

Fig. 6 is a side-view of the emergency brake lever and electric connections, the throwing of which off and into the non-braking position by unauthorized persons 80 will bring to view the thief-trapping signal.

Referring to the drawings, the reference letter A designates the vehicle dash, B the wind-shield plate and C the sign casing or housing inclosing the visual signal-plate D, 85 and its actuating mechanism; which signal-plate is usually and preferably of some opaque substance having on the outer end as indicated in Fig. 1, on either side a word such as "Stolen," or other like words, signs 90 or symbols, indicating unauthorized use of the vehicle.

The outer wall 10 of the casing or housing C is secured to the rectangular box-portion of same extending from the back wall 10', 95 end pieces 11, and top and bottom pieces 11', by means of suitable securing screws 12, screwing into securing lugs 13, formed integral with or secured to the end walls 11, and top and bottom walls 11', at the corners, this portion of the housing being usually a casting. Such housing C is secured to the dash A by screws 14, or rivets (preferably the latter), passing through securing-lugs 15 formed integral with the housing. 100

Located adjacent to the back wall 10' of

the housing and within the same is the normally concealed visual-alarm sign-plate D which reciprocates in and out of the slot 16 in the right hand end wall 11', and has its 5 rear end always located in the narrow rear plate-chamber 4, and is provided at the outer end with an enlarged outwardly flared head 16', so that when in the closed position shown in Figs. 1, 3 and 4 when the sign is 10 within the casing and concealed from view, such flare-head 16', will close the slot 16, so as to prevent entrance of dirt or moisture to the interior of the housing. The sign-plate D is horizontally supported in such 15 slot 16 at the height shown at 17' (Fig. 1) by reason of resting and sliding upon the bottom of the slot 16 in the end wall 11, and the end walls 18 and 18', of the lock-housing 19', and the front plate 20 of such lock-housing 19 is secured in place to the wall 10' 20 of the main-housing C, in any desired manner, usually by means of screws 21.

Within the lock-housing and somewhat loosely mounted therein so as to freely reciprocate up and down therein, is a lock rack-bar 22, having on the upper edge a plurality of rack-teeth 23 of any desired number, usually eight as shown; which rack-bar is provided at the left-hand or rear end, with 25 a downwardly depending slide-lug or fin 24, and at the right-hand end with a similar lug or fin 24', from the lower end of which extends outward through the end wall of the lock-housing an electric contact-member 30 25 passing out through the slot 26, such toothed ratchet-bar being, (when the vehicle is to be operated by the owner) drawn down into the position shown in Fig. 2, so that the ratchet teeth are below the top of the 40 lock-housing so as to be out of contact with the pawl 27, vibratorily mounted on the pivot stud-screw 28, secured in the signal-plate D, and having the upper stop-lug or fin 29 contacting with the stop-pin 45 29' mounted in the signal-plate D, against which stop-pin the stop-lug 29 of such pawl is kept normally forced by a suitable spring 30, usually of the straight-pressure form indicated, secured to the screw or stud pin 50 30', mounted like the pin 29' in the sign-plate D.

The lock for setting the signal to trap a thief or to render the same inoperative when the vehicle is to be used by any authorized 55 persons, is of any suitable construction; but is usually for greater security, what is known as a Yale lock of the paracentric type, having the cylindrical tumbler-casing 9 formed integral with or secured to the 60 lock-mechanism for setting the device to trap a thief, or to render the same inoperative when the vehicle is to be operated by an authorized person, being put into or out of automatically operated signaling or non- 65 signaling position, by a suitable key by

authorized persons; and such lock mechanism being well known in the art, I have not deemed it essential to show the same herein, in detail, save to show that the tumbler F of the lock is provided with a lift-lug or 70 cam-piece H, which when in the top position shown in Fig. 1, will force the toothed rack-bar 22, against the tension of the springs 31 and 31', up into the locking position and when thrown to an angle of 90 degrees into 75 the horizontal (Fig. 2) will allow the springs 31 and 31', to draw such rack-bar down within the lock-housing into the non-operative position shown in dotted lines in such Fig. 2. 80

The visual signal-alarm-plate D has secured adjacent to the rear end thereof a post or pin 37, to which is secured a throw-spring 38, secured in like manner to a like post 37', secured to the front-plate 10' of the 85 housing as indicated in Figs. 1 and 3.

Vibratorily supported upon a pivot-pin 39, secured to the signal-alarm-plate D, is a vibrating lock-pawl 40, having the pawl hook 40', having its outer front face slanted, or if straight, being of such length and being so pivoted, and it being by gravity held in such position, that when the alarm-plate D after being thrown into the indicated position, is pushed back into the housing, such pawl will ride up over the right hand slanted upper end 41, of the solenoid lock-bar 42, normally thrown upward into the locking position shown in Fig. 1 (against the tension of a coil-spring 43), located 90 between the spring-flange or collar 44, and upper securing-flange 48, of the electric solenoid-coil 49, energized by the conductor-wires 50; and the like wire 51 connected with the contact-plate 52, also rigidly 95 secured to the inner wall of the housing or casing. And located below the same and secured in like manner is a like plate 52'; carried by a like insulating-block 53'; and connected with the conducting-wire 54; and usually and preferably the solenoid-coil 49 is secured in proper place below the pawl 40, upon an insulating block 55, secured to the wall 10 of the main housing, as shown 100 in Fig. 3. 105

Supported in the lock-housing 19, upon a suitable insulating-block is an electric-contact-spring member 56 in constant sliding contact with the contact-bar 25, connected with the lead-wire 61 (Figs. 1 and 120 5) connected with the battery or electric-supply K, through the plug cut-out P by way of the wire 62, a wire 63 connecting with the ground-wire 60.

The parts being in the position shown in 125 Figs. 1 and 3 (with the visual alarm signal-plate D, as shown in full lines, drawn fully back within the casing or housing, out of view, and held in such position against the tension of the throw-spring 38, by the vi- 130

brating pawl 40, in contact with the solenoid-bar 43) when the parts are in such position with the toothed ratchet-plate in the extreme upward position, the pawl 27 5 will have its point 27' below the top of the ratchet-teeth, as shown in Fig. 1; and the electric contact switch-bar 25 will be in contact with the upper contact-plate 52, connecting with the solenoid-coil 49 by the 10 wire 51; while the other end wire 50 of the coil is connected with the common-ground wire, usually some portion of the main-frame of the vehicle as indicated in the diagram Fig. 5 at G.

15 The contact-plate 52' is connected with the lead-wire 54', having the make and break starting switch 55, when in the closed position, closing the circuit through the motor starter S by way of the wires 56 and 20 57, ground-wire 60, wire 63, battery K and wires 62 and 61, by way of the plug cut-out P; and it will be seen upon examination of Fig. 5, that the starter S can only be actuated to start the motor when 25 is closed to 52', and the plug is inserted in the plug cut-out P, and the starter-switch 55 and 55' also closed, which will only be when the locking mechanism is, (by an authorized person using a suitable key) 30 thrown down into the position shown in Fig. 2, with 25 in contact with the contact-plate 51', and the plug is inserted in P. The ignition circuit of the driving motor M is from the battery K, by way of 62, 35 P, 61, 25, 52', 54, switch 64, wire 65, ignition plug of M, and wires 66, 60 and 63 back to K.

The hereinbefore described mechanism is so constructed and arranged that while it 40 protects the vehicle from theft, when put into movement under its own power by an unauthorized person, it will not prevent its being stolen and carried away by towing, etc., and to prevent thefts of this character, 45 the vehicle is provided with a subsidiary-signal actuating mechanism which is brought into operation upon the release of the braking mechanism usually what is known as an emergency-brake, the actuating 50 lever and locking mechanism of which is shown in detail in Fig. 6, wherein U designates the rack-sector, vibratory supporting the emergency-brake hand-lever 80, upon the pivot pin or bolt 81; and being 55 locked in the braking or non-braking position by the locking dog-rod 82; having the releasing handle 83, such lever 80 is connected below the pivot bolt 81, with the brake actuating lever 84, by the short-lever 60 or extension 85. The brake when set to the braking position so that the vehicle cannot be moved either by its own power, or by towing, having the lever 80 in the position shown in dotted lines at 80' (Fig. 6); and 65 when in the brake-releasing position, being

as shown in full lines therein. Mounted upon a suitable insulating base-block 86, secured to the toothed locking-sector U, is a spring contact member 87, extending forward over the sector, and secured to the 70 lever 80 in like manner upon a like insulating block 86', is a coacting spring contact-member 88, which when the lever is in the brake releasing position shown in Fig. 6, full lines, contacts with the contact member 75 87 to close the electric circuit throwing the thief signal to view.

The contact member 87 being connected with the wire 62, by a wire 89 and the contact 88, being connected with the switch 80 contacts 25 and 52, connected through the theft releasing solenoid-coil 49, wires 50, 60 and 63, with the other pole of the battery K, as clearly indicated in diagram in Fig. 5; the wire 90 connecting the contact 88 with the 85 solenoid through 25, 52 and 51 preferably passing down to the pivot point 81, of the brake-lever 80, so that there will be no distortion of the wire upon the movement of such lever. And it will be seen that upon 90 the throwing of the brake by unauthorized persons, out of the braking position, when the lever 80 is in the releasing position shown in full lines in Fig. 6, the contact of 88 with 87 will close the circuit through 95 the solenoid 49, even though the plug P has not been inserted so as to close the ignition circuit; and that the sign will be instantly released, to indicate that such machine is in the hands of unauthorized persons, even 100 though being towed and not under its own power.

The lighting or lamp circuit (Fig. 5) comprises the wires 62, 62', switch 67, resistance 68, and wires 69, 70, 71, 72, 73, 74, 105 67, 75, G, 60 and 63, in which are included the head-lights L L, tail-light T, and side-light R.

It will at once be seen from the drawing and description, that so long as the ratchet-lock is in the upper and thief-trapping position shown in Fig. 1, with the circuit through 54 broken, that even by insertion of a contact-plug in P that the starter S, cannot be energized and operated; and that 110 upon the insertion of such plug in P, the solenoid-coil 49 being energized and the pawl 40 released, the alarm-signal-plate D, will be thrown out into view by the throw-spring 38, (such throw being limited by the 115 stop-pin or screw 70, extending into the stop-slot 70' of such plate D) and will be locked against unauthorized replacement in its housing, by contact of the pawl 28 with the teeth 23 of the rack-bar 22.

It is evident that many various changes and modifications in the construction and arrangement of the several parts of my thief-catching apparatus herein shown, may be made without departing from the scope of 120 125 130

my invention, and I do not intend to limit myself strictly to the exact forms shown.

I claim:—

1. A thief-indicating device comprising, a normally concealed visual signal for vehicles, said signal having words or symbols that indicate such vehicle is being stolen; locking mechanism for retaining the signal in non-visible position when the vehicle is being driven by an authorized person, and setting means for automatically releasing the visual indicating means, and bringing the same to view upon attempt being made by an unauthorized person to operate the vehicle; and for locking such signal against re-concealment by an unauthorized person.
2. A thief-indicating device comprising a housing, a thief-indicating sign adapted to be moved to position for concealment in said housing and to be moved to position for display, means for moving said sign from position for concealment to position for display, locking means on said sign, electric means for engaging said locking means on said sign and releasable therefrom, for retaining the sign in position for concealment, pawl and rack means for retaining the sign in position for display, locking means engageable with said rack means for locking the sign in position for display, and means for operating said electric retaining means to release the locking means on said sign to allow the operation of the means for moving the sign from position for concealment to position for display.
3. A thief-indicating device for a motor vehicle having means for controlling the driving wheel revolution of such vehicle, said device comprising a housing attachable to the motor vehicle, a thief-indicating sign adapted to be moved to position for concealment in said housing and to be moved to position for display, means for moving said sign from position for concealment to position for display, locking means on said sign, an electric circuit, electric means for engaging said locking means on said sign and releasable therefrom, and comprised in said electric circuit, for retaining the sign in position for concealment, pawl and rack means for retaining the sign in position for display, locking means engageable with said rack means, and means comprised in said electric circuit for engaging the before-mentioned means for controlling the motor vehicle driving-wheel revolution, whereby movement of said means for controlling will operate said electric retaining means to release the locking means on said sign to allow the operation of the means for moving the sign from position for concealment to position for display.
4. A thief-indicating device comprising a housing, a thief-indicating sign adapted to be moved to position for concealment in said
5. A thief-indicating device comprising a housing, a thief-indicating sign adapted to be moved to position for concealment in said housing and to be moved to position for display, a spring for moving said sign from position for concealment to position for display, a pawl on said sign, electric means on said housing for engaging said pawl, and releasable therefrom, to retain the sign in position for concealment, a pawl and rack carried by said sign for retaining the sign in position for display, locking means engageable with said rack for locking the sign in position for display, and means for operating said electric retaining means to release the pawl on said sign to allow said spring to move the sign from position for concealment to position for display.
6. A thief-indicating device comprising a housing attachable to a vehicle, a thief-indicating sign adapted to be moved to position for concealment in said housing and to be moved to position for display, a spring for moving said sign from position for concealment to position for display, a pawl on said sign, an electric circuit, a solenoid on said housing and comprised in said electric circuit for engaging said pawl, and releasable therefrom, to retain the sign in position for concealment, a pawl and rack carried by said sign for retaining the sign in position for display, a lock engageable with said rack for locking the sign in position for display, means for unlocking said lock, and means comprised in said electric circuit for operating said solenoid to release the pawl on said sign to allow said spring to move the sign from position for concealment to position for display.
7. A thief-indicating device for a motor vehicle having a brake-lever, said device comprising a housing attachable to the motor vehicle, a thief-indicating sign adapted to be moved to position for concealment in said housing and to be moved to position for display, a spring for moving said sign from position for concealment to position for display, a pawl on said sign, an electric circuit, a solenoid on said housing and comprised in said electric circuit for engaging said pawl and releasable therefrom, to retain the sign

in position for concealment, a pawl and rack carried by said sign for retaining the sign in position for display, a lock engageable with said rack for locking the sign in position for display, means for unlocking said lock, and means engaging the brake-lever of the vehicle and comprised in said electric circuit, whereby movement of the brake-lever will operate said solenoid to release the pawl on said sign to allow the operation of said spring, to move the sign from position for concealment to position for display.
